UNITED STATES PATENT OFFICE.

GUSTAV KEINING, OF SOEST, GERMANY.

TYPEWRITING MACHINE.

Application filed February 25, 1928, Serial No. 257,070, and in Germany August 25, 1927.

Improvement in typewriting machines.

My invention relates to typewriters and more particularly to that class of typewriters by means of which shorthand or steno-
graphic script may be written.

One object of my invention is to provide a typewriter in which the keys may be arranged in the customary manner so that everybody accustomed to the standard ar-
rangement of the keyboard may easily learn the use of my improved shorthand type-
writer.

Another object of my invention consists in the provision of a typewriter by means
15 of which shorthand script as well as script in ordinary letters may be typed, as desired.

From another aspect an object of my in-
vention is a typewriter for stenographic
20 script in which the distance between the
typed lines must not by necessity exceed the
distance which is ordinarily in use in type-
writing script in ordinarily long hand let-
ters.

My invention satisfies an urgent demand
25 for a typewriting machine by means of
which a speed in typing may be attained
which is far superior to the speed of ordi-
nary typewriting and equals at least that
30 of stenographing by hand. The typewrit-
ing script looks very similar to the
handwritten script and may easily be
read by everybody familiar with the par-
ticular system used. The invention, there-
35 fore, does away with the inconveniences and
disadvantages caused by the well known fact
that ordinarily hand written stenographic
script can be read and transformed into long
hand script only by the same person who
40 took the dictation in short hand.

By means of my invention it is possible,
therefore, to have a letter written in short-
hand by one person and transformed into
ordinary typewritten script by another per-
son.

My invention particularly contemplates
the use of a system of stenography in which
a consonant, either a single or a composite
consonant, and the vowel associated there-
with are represented by a single simple
50 shorthand sign, and in which for represent-
ing different syllables comprising the same
consonant associated with different vowels,
signs are used which are partly alike, signi-
fying the associated vowel by certain char-

acteristics in their configuration and not, as
in other stenographic systems, by their po-
sition in relation to the line.

I prefer the use of such shorthand system
to the use of the mentioned other systems in
which the same sign is employed for repre-
senting a consonant associated with differ-
ent vowels and is differently positioned in
relation to the line to express various vowels,
because a change in the position of the sign
has the disadvantage that the distance of
the lines must necessarily exceed the space
ordinarily used in typewriting.

Other more specific objects will appear
from the description hereinafter and the
features of novelty will be pointed out in
70 the claims. For the purpose of illustrating
an example of the invention I have shown it
in the accompanying drawings as embodied
in a typewriter such as shown and described
in the German Patent No. 211,568.

Fig. 1 is an elevation, Figs. 2 to 4 are sec-
tions along the respective section lines indi-
cated in Fig. 1, Fig. 5 shows an example
of the types, Fig. 6 a detail on a small scale.

10 indicates the customary paper carrier
or paper cylinder which is journaled in the
bearings 11 forming part of a frame consist-
ing of two lateral posts 12 connected with
each other by an integral plate 13^a. The
posts 12 are shiftable mounted in guideways
13 which are attached to a frame 14. The
frame 14 is movable or transportable in
axial direction with respect to the cylinder
10 and is acted upon by a mechanism
which moves it step by step to the left when
the keys of the typewriter are successively
90 pressed down. As such mechanisms are well
known in the art and do not form part of
the present invention, a description and il-
lustration thereof is deemed dispensable
herewith. The opposed faces of the posts
12 are provided with grooves for slidably
95 accommodating a frame 15 which may be
adjusted in various definite positions relative
to the posts 12.

For this purpose, brackets 16 are attached
to the plate 13^a and a shaft 17 is journaled
therein carrying at its ends levers 18 pro-
vided with hooks 19. The frame 15 is
formed at either side with a cover plate 20
provided with two holes 21 and 22 register-
ing with the respective hook 19. The shaft
17 is provided with a handle 23 and a spring

24 is inserted between the same and the post 12 tending to hold the hooks 19 in engagement with the holes 21 or 22. When the handle is pressed towards the post 12, the shaft 17 is turned thereby disengaging the hooks 19 from the holes. The posts 12 may then be lowered by hand until the holes 22 are in registry with the hooks 19. Upon releasing the handle 23 the hooks, owing to the action of the spring 24, will slip into the holes 22 and will hold the posts 12 and the frame 15 in their new relative position.

In order to facilitate the manual adjustment of the posts 12 relative to the frame 15 and to avoid a jamming of these parts, special provisions are made to prevent an angular displacement of the posts 12. These provisions comprise a shaft 25 journaled in the brackets 16 and having a pinion 26 fixedly attached to each end. The pinions 26 are meshing with teeth 27 cut into the opposed edges of the cover plates 20. A displacement of the one post 12 relative to the frame 15 causes a rotation of the co-ordinated pinion 26 and thereby a corresponding displacement of the other post 12, whereby the posts 12 are prevented from jamming.

The frame 15 forms two horizontal flanges 28, 29 forming a guideway for a roll 30 carried by lever 31 which is keyed to a shaft 32. The shaft 32 is supported in stationary bearings attached to the frame of the typewriting machine and is provided with a mechanism not shown, for adjusting the shaft 32 and its lever 31 in one of three angular positions indicated in dotted lines. As such mechanism are well known in the art it will not be described in detail. By this adjustment of the shaft 32 the roll 30 may be lowered into the positions 30^a or 30^b. The frame 15 and the posts 12 connected with the roll are correspondingly shifted in the guideways 13.

The paper cylinder 10 co-operates with a type carrier 33 carrying two groups of types. The one group comprising the types 34, 35 and 36 is intended for use in writing shorthand script of some graphic system as distinguished from geometrical systems. The distance of these types equals the amount by which the frame 15 may be raised or lowered by action of the afore-mentioned angular adjustment of the shaft 32. The types 37, 38, 39 which serve for writing ordinary script are arranged at the same distance from each other. In the position shown in the drawings the frame 15 occupies its uppermost position. In this position the type 34 is co-operatively correlated to the paper cylinder 10 and may be brought into printing position by striking the key 40 as will be easily understood from Fig. 5 which is self explaining, and does not need a description as the details shown therein are simple and well known in the art. By

changing the angular position of the lever 31 which ordinarily is effected by pressing upon special keys, one key being provided for the uppermost position and another key for the lowermost position of the lever 31, the frame 15 is lowered by one or two steps and either the type 34 or the type 36, as desired, is brought into operative position.

As the distance between corresponding types of both groups, such as the distance between the types 35 and 38, corresponds with the distance between the holes 21 and 22, the paper carrier occupies the same position relatively to the respective opposed group of types on the type carrier regardless of whether the hooks 19 are engaging the holes 21 as shown or the holes 22.

As the three types 34, 35 and 36, being carried by a common type carrier, are coordinated to the same key they serve for printing shorthand signs which represent the particular consonant with which said key is marked and various vowels coordinated with said consonant. The configuration of three types, therefore, is preferably such that a certain part thereof is equal in all three types. This part is characteristic of the particular consonant, the remainder of the three configurations, however, is differentiated in shape to express various vowels which may be associated with said consonant to form a syllable. The term "consonant" as used herein and in the claims is intended to cover also composite consonants like "st" or "ch" etc. If three shorthand types are coordinated to the key marked with a consonant, as in the example described, only three different signs are available for distinguishing the various vowels but my experience has shown me that three signs are perfectly sufficient for practical purposes. In this case, each sign, designates a vowel of a vowel group and the reader of the script must guess from the sense thereof which particular vowel of that group is the one which is meant by the sign. In the German language the three groups comprise e, ei, i and eu, or a, au, ä and äu, or o, ö, u, and ü respectively.

In Fig. 6 I have illustrated by way of example the configuration of the types 34, 35 and 36 on an enlarged scale. All three types are coordinated to a key marked with the consonant D. That part of each type situated above the dotted line is equal to the corresponding part of the other two types. The term "equal" applied to these parts does not only indicate the identity in shape but it characterizes also the identic position which these parts assume in printing position in relation to the line. Those parts of the configurations which are situated below the dotted lines differ from each other and indicate the vowel associated with "d". The type 35 may, therefore, designate in the

German language, for instance, de, dei, di, or deu, the type 35 da, dau, dä or deu, and the type 36 do, dö, du or du.

The lower group comprising the types 37 5 38 and 39 corresponds with the conventional arrangement. The type 37 represents a sign "+" whereas the types 38 and 39 serve for typing the ordinary letters "d" or "D" respectively.

10 From the foregoing description it will be apparent that the invention in a broad aspect consists in the provision of at least three shorthand types of configurations having an equal part to represent the consonant of 15 the key coordinated with said types, and having a different part, such as the parts situated below the dotted lines in the illustrative example, to represent a vowel or a vowel group. Furthermore, selecting 20 means, such as the adjustable shaft 32 with its associated parts and the adjustable posts 12, must be provided by means of which any one of the shorthand types may be selected for typing, similar to the optional selection 25 in ordinary typewriters between small letter types and capital letter types which are also coordinated to the same key and may be selected by special keys.

The fact that a given consonant is always 30 written by means of the same key no matter with what vowel it is associated, affords the valuable advantage that a key board may be used which substantially corresponds with the standard arrangement. This renders it 35 possible to provide ordinary types in coordination with the stenographic types so that both kinds of script may be written on the same machine without requiring special study and exercise, or any other adjustment 40 than the simple shifting of the posts 12 from their one position into their other position.

What I claim is:—

1. In a typewriting machine, the combination comprising a key provided with a mark 45 representing a consonant, a type representing said consonant in an ordinary small letter, a type representing said consonant in a

capital letter, three shorthand letter types of configurations having an equal part to represent said consonant and a different part to 50 represent a vowel group associated with said consonant, a mechanism operatively connecting said key with said types to cause upon the pressing of the key the movement of one of the types into printing position and selecting means for selecting any one of said three types for the movement into said position.

2. In a typewriting machine the combination comprising a key provided with a mark 60 representing a consonant, three shorthand letter types of configurations having an equal part to represent said consonant and a different part to represent a vowel group associated with said consonant, a mechanism 65 operatively connecting said key with said types to cause upon the pressing of the key the movement of one of the types into printing position and selecting means for selecting any one of said three types for the movement into said position.

3. In a typewriting machine, the combination comprising a key provided with a mark representing a consonant, a type carrier having two groups of types one group including 75 an ordinary capital letter type and an ordinary small letter type of said consonant, the other group including three shorthand letter types of configurations having an equal part to represent said consonant and a different part to represent a vowel group associated with said consonant, a paper carrier, an operative connection between said key and said type carrier to move the latter towards said paper carrier and a selecting 80 mechanism for bringing said paper carrier and any desired type of said type carrier into printing position to each other thereby 85 permitting the same key to be used for typewriting a shorthand sign as well as an ordinary letter.

In testimony whereof I affixed my signature.

DR. GUSTAV KEINING.
